[57] CLAIM

The ornamental design for a spot weld removal tool, as shown and described.

DESCRIPTION

FIG. 1 is a perspective of my novel spot weld removal tool; FIG. 2 is a top plan view thereof;

FIG. 3 is a front elevation of FIG. 2;

FIG. 4 is an elevation similar to FIG. 3 but turned approximately 45°;

FIG. 5 is a right side elevation of FIG. 2; and,
FIG. 6 is a bottom plan view thereof.

The rear elevation and left elevation are mirror images of the front elevation and right elevation, respectively.
